INTERNAL-COMBUSTION ENGINE.

1,197,158.

Specification of Letters Patent. Patented Sept. 5, 1916.

Application filed January 12, 1916. Serial No. 71,818.

To all whom it may concern:

Be it known that we, HENRY C. STOLL and 5 GEORGE W. GAY, citizens of the United States of America, residing at New York city, and Elmhurst, Long Island, New York, respectively, have invented a new and useful Internal-Combustion Engine, of which the following is a specification.

This invention relates to the valve mechanism of engines of this character and the general objects of the invention are to improve and simplify this mechanism, to reduce the number of parts, to lighten the reciprocating parts, to render the valve mechanism smooth in action and quiet in operation and to produce through these improvements an engine of increased power and greater efficiency. In the accomplishment of these objects we employ a valve sleeve in sliding engagement with the cylinder wall and controlling one port or set of ports therein and a valve segment slidingly engaged in a channel in the valve sleeve and controlling the other port or set of ports in the cylinder wall. According to a preferred embodiment the valve sleeve surrounds and slides over the outside surface of the cylinder and there are two valve segments, interconnected to move as a unit and 20 slidingly engaged in oppositely disposed longitudinally extending grooves or channels in the valve sleeve.

Other features of the invention and details of construction will be made apparent 25 as the specification proceeds, attention being directed to the accompanying drawing which illustrates the invention embodied in several preferred forms.

In this drawing:—Figure 1, is a longitudinal sectional view taken through the cylinder of an engine embodying the invention, parts being broken away and some parts being shown in elevation. Fig. 2, is a transverse sectional view of the same taken 30 substantially on the plane of the line 2—2 of Fig. 1. Fig. 3, is a detail perspective view on a reduced scale of the valve sleeve and the segmental valve illustrated in Figs. 1 and 2. Fig. 4, is a similar view of a 35 slightly modified form wherein the position of the segmental valve is reversed with respect to the valve sleeve.

Referring now first to Figs. 1 and 2, 7 designates an engine cylinder in which 40 operates a piston 8, this piston being of any usual or preferred construction and con-

nected with the crank shaft 9 as by means of a suitable connecting rod 10. In the form of the invention herein illustrated, the valves work over the outside of the cylinder 45 and the cylinder is therefore made with a smooth cylindrical outer surface as illustrated. The side wall of the cylinder is in the illustration provided with a pair of oppositely disposed in-take ports 11 and with 50 a pair of oppositely disposed exhaust ports 12, only one of these ports 12 appearing in Fig. 1, it being understood that a similar port is provided in the wall opposite this port. The respective pairs of ports are controlled by valves in the form of a sleeve 15 and a pair of interconnected valve segments 16, the sleeve being slidingly engaged over the outer cylindrical surface of the cylinder and the valve segments being slidingly engaged in oppositely disposed longitudinally extending channels or grooves 17 formed in the sleeve. In the engine herein illustrated the sleeve constitutes the in-take valve and the inter-connected valve segments constitute the exhaust valve, the intake valve sleeve being shown provided with oppositely disposed ports 11' therein registering with the intake ports 11 and the exhaust valve segments being shown provided with exhaust 60 ports 12' registering with the cylinder exhaust ports 12.

In the first embodiment of the invention illustrated, the segmental valve slides within the sleeve valve, the grooves in which the segments slide therefore being formed on the inner wall of said sleeve. The valve segments are suitably connected together so as to move as a single unit, in the present instance by integral ring portions 18 and 19 65 at the upper and lower ends thereof. The upper connecting ring 18 is shown reduced or cut away at diametrically opposite points as indicated at 20 so as to slide within the sleeve when assembling the valve structure. The sleeve is internally reduced at its lower end as indicated at 21 to receive the lower connecting ring 19. The sleeve valve is prevented from interfering with the function 70 of the other valve by providing it with openings 22 in the channeled portions thereof in line with the ports (12') in the valve segments.

Suitable gearing for operating the valves is provided, said gearing comprising in the 75 illustration a pinion 25 on the crank shaft meshing with the gear 26 on the valve op-

erating shaft 27, said shaft having cranks or cranked portions 28 and 29 connected by the links 30, 31 and push rods 32 and 33, respectively, with the intake and exhaust valves. The valves are shown provided with outstanding lugs 32' and 33' at their lower ends with which the push rods 32 and 33 respectively are connected.

In Fig. 1 the parts are illustrated in the position they occupy when the piston is moving upward on its compression stroke, and has completed the first half of this stroke. In this view the exhaust valve is at the extreme upper limit of its stroke with the port 12' therein above the exhaust port 12 in the cylinder wall and the intake valve is approaching the upper limit of its travel with the intake port 11' therein above the intake port 11 in the cylinder wall. Both intake and exhaust ports, are, therefore, closed entirely. The ratio of the gearing between the crank shaft and valve operating shaft is illustrated as four to one, and it will be understood that for one cycle of operation the valves will be actuated to carry the ports therein from a position at one side of the cylinder ports to a position at the other side of the same, and that for the next cycle of operation said valves will be actuated to carry the ports therein from said last mentioned position to the position at the other side of the cylinder ports. This gives a relatively slow valve action so that vibration, friction and wear are reduced to a minimum.

The valves are preferably incased and protected by a cylindrical housing 35 surrounding the valves and bolted in this case to the engine base 36. This housing is shown utilized for securing the cylinder also to the base by providing it with a tubular extension 37 in the head thereof, which engages the head of the cylinder and thereby holds the cylinder firmly to the base. This tubular dependent extension 37 provides a pocket protecting the spark plug 38 which is let into the cylinder.

The ring 18 which connects the upper end of the valve segment 16 is made with a large enough internal diameter to fit around this tubular dependent extension 37, as indicated in Fig. 1.

In Fig. 4 we have illustrated how the relation of the valve sleeve and the segments 55 may be reversed, the channels 17' in the valve sleeve 15' being in this case formed in the outer wall of the sleeve, and the segment 16' being arranged to work in these channels in the outer surface of the sleeve. The operation of this form is practically the same as the first form described.

From the foregoing, it will be clear that the valve mechanism of our invention is simple in construction and relatively light in weight and further, that by reason of

the opposite disposition of the valve ports, the pressure is substantially balanced on the valves and there is, therefore, no undue friction at any point. Another important feature consists in placing the valve actuating shaft, as illustrated, in the same vertical plane with the crank shaft, and operating the valves by push links disposed at opposite sides of the cylinder and in vertical alinement with the crank shaft. This makes a very compact engine which has less transverse width than an engine having the usual valve construction.

What we claim is:

1. In an internal combustion engine, a cylinder having ports in the side wall thereof, a sleeve in sliding engagement with said cylinder wall and controlling one of the ports therein, said valve sleeve having a longitudinal channel therein, a valve segment slidably engaged in said channel in the valve sleeve and controlling one of the other ports in the cylinder wall, a crank shaft, a piston in the cylinder operatively connected with said crank shaft and valve operating gearing from the crank shaft to said valve sleeve and segment respectively.

2. In an internal combustion engine, a cylinder having ports in the side wall thereof, a sleeve in sliding engagement with said cylinder wall and controlling one of the ports therein, said valve sleeve having oppositely disposed longitudinal channels therein, valve segments slidably engaged in said oppositely disposed channels in the valve sleeve and controlling other ports in the cylinder wall, a crank shaft, a piston in the cylinder operatively connected with said crank shaft and valve operating gearing from said crank shaft to the valve sleeve and valve segments respectively.

3. In an internal combustion engine, a cylinder having ports in the side wall thereof, a sleeve in sliding engagement with said cylinder wall and controlling one of the ports therein, said valve sleeve having oppositely disposed longitudinal channels therein, interconnected valve segments working as a unit and slidably engaged in said channels in the valve sleeve and controlling other of the ports in the cylinder wall, a crank shaft, a piston in the cylinder operatively connected with said crank shaft and valve operating gearing from said crank shaft to said valve sleeve and to said interconnected valve segments.

4. In an internal combustion engine, a cylinder having ports in the side wall thereof, a sleeve surrounding and slidably engaged over the outside of said cylinder and controlling certain of the ports therein, said valve sleeve having substantially opposite longitudinally extending channels therein, interconnected oppositely disposed valve segments slidably engaged in said

channels in the valve sleeve and controlling other of the ports in the cylinder wall, a crank shaft, a piston in the cylinder operatively connected to said crank shaft and 5 valve operating gearing from said crank shaft to the valve sleeve and to the interconnected valve segments respectively.

5. In an internal combustion engine, a cylinder having ports in the side wall thereof, 10 a sleeve surrounding and slidably engaged over the outside of said cylinder and controlling one of the ports therein, said valve sleeve having a longitudinal channel therein, a valve segment slidably engaged in said 15 channel in the valve sleeve and controlling one of the other ports in the cylinder wall, a crank shaft, a piston in the cylinder operatively connected with said crank shaft and 20 valve operating gearing from the crank shaft to said valve sleeve and segment respectively.

6. In an internal combustion engine, a cylinder having two sets of oppositely disposed ports in the side wall thereof, a sleeve in sliding engagement with said cylinder wall and controlling one set of oppositely disposed ports, said sleeve having oppositely disposed longitudinal channels therein in line with the other set of ports, oppositely disposed interconnected sliding valve segments working as a unit in said longitudinal 25 channels and controlling the second set of oppositely disposed ports in the cylinder wall, a crank shaft, a piston in the cylinder connected with said crank shaft and valve operating gearing from said crank shaft to 30 said valve sleeve and the interconnected valve segments.
